A. C. WEINS

COLLAPSIBLE MEGAPHONE

Filed March 28, 1923

Inventor
Anthony C. Weins.

El. Bradforth

Attorney

UNITED STATES PATENT OFFICE.

ANTHONY C. WEINS, OF RACINE, WISCONSIN.

COLLAPSIBLE MEGAPHONE.

Application filed March 28, 1923. Serial No. 628,341.

To all whom it may concern:

Be it known that I, ANTHONY C. WEINS, a citizen of the United States, residing at Racine, in the county of Racine and State of Wisconsin, have invented certain new and useful Improvements in Collapsible Megaphones, of which the following is a specification.

My said invention relates to a collapsible megaphone and it is an object of the invention to provide a device of the character described which can be folded easily and without damage and which can readily be restored to operative position.

15. A further object of the invention is to provide such a megaphone with a handle and with means for holding the megaphone firmly in open or operative position.

20. Referring to the accompanying drawings which are made a part hereof and on which similar reference characters indicate similar parts,

25. Figure 1 is a side elevation partly in section of the megaphone in collapsed position,

Figure 2 is a plan of the same with parts broken away,

Figure 3 is a perspective of the megaphone in operative position, and

30. Figure 4 a perspective of the megaphone collapsed.

In the drawings reference character 10 indicates a mouthpiece, preferably of aluminum or other metal, which has a central opening surrounded by an inturned central flange and an outer flange extending over flat side members 11 at one end thereof and serving to hold the side members in open position as indicated at Figure 1. The side members may be made of indurated fiber, 35 cardboard or other like material. The side members are connected by strips 12 of leather or other flexible material preferably all located externally of the megaphone, for better appearance, and are provided with buttons 13, 14 and 15. A strap 16 is secured at one end by a rivet 17 to a side member 11 and at the other end by rivet 18 to mouth piece 10. Between its ends the strap passes under a guide 19 also secured to said side member. In the open position of the megaphone a snap 20 engages the button 14 while a snap 21 on a short strap secured to the flange of the mouthpiece at its opposite side engages the button 15. In this way it will

be seen that the parts of the megaphone are 55 securely held together while the hand holding the strap 16 will by reason of the guide 19 be prevented from disengaging the snap 20. On the contrary the tendency is to pull the strap 16 and tighten the hold of the 60 snap 20 on the button 14.

In order to collapse the megaphone snaps 21 and 20 are released and the parts are folded in the relation shown in Figure 4 after which the strap 16 is drawn taut and 65 the mouth piece 10 is folded down on the opposite side of the device bringing the snap 21 into position over the button 13 to which it is secured. This holds the parts securely in the position shown in Figure 4 forming 70 a flat package which can be placed in the pocket or other receptacle and be practically safe from injury. It will be seen that either in the folded or half folded position the device may conveniently be utilized as a 75 fan, should it be desired to make such use of it.

While I have shown the device as flat-sided, this being the most effective and durable, I do not limit myself thereto, as 80 curved side pieces may be desirable in some instances. The device shown in the drawings and described in the specification may also, as will be obvious to those skilled in the art, be changed in other respects, as by increase 85 in the number of sides, and may be otherwise modified without departing from the spirit of the invention, the true scope of which is shown in the appended claims.

Having thus fully described my said invention, what I claim as new and desire to secure by Letters Patents, is:

1. A collapsible megaphone comprising side members, hinges connecting them at adjacent edges, a mouth piece having an annular polygonal flange adapted to fit closely over the side members at one end thereof, and a circular flange adapted to fit into and tangentially contact the side members, said mouth piece holding the side members in 100 open position, and means to secure the mouth piece in place, substantially as set forth.

2. A collapsible megaphone comprising side members, a mouth piece having a polygonal flange adapted to fit over said side 105 members to hold them in open position and a circular flange adapted to fit into and tangentially contact the side members, a strap

secured to one of said side members and to the mouth piece and serving as a handle for the megaphone, substantially as set forth.

3. A collapsible megaphone comprising 5 side members, a mouth piece having a flange adapted to hold said side members in open position, a strap secured to one of said side members and to the mouth piece and serving as a handle for the megaphone, means for 10 fastening the strap to the side member closely adjacent the mouth piece and means at the opposite side of the megaphone for attaching the mouth piece releasably to said side member of the megaphone, substantially 15 as set forth.

4. A collapsible megaphone comprising flat side members, a mouth piece having a flange adapted to hold said side members in open position, a strap secured to one of said 20 side members and to the mouth piece and serving as a handle for the megaphone, a guide on said side member adjacent the mouth piece and a button and snap located one on the strap and the other on the side 25 member beneath it between the guide and the mouth piece whereby tension on the handle portion of the strap serves to hold said snap in engagement, substantially as set forth.

5. A collapsible megaphone comprising flat side members hinged together at their edges, a mouth piece adapted in one position to hold the side members in open position, a strap secured to one side member and to the 35 mouth piece, a button on the opposite side piece, a snap on the mouth piece adapted to be engaged over said button and a button on an intermediate side member over which said snap is adapted to engage in the folded 40 position of the megaphone, substantially as set forth.

6. A collapsible megaphone comprising flat side members, a handle secured to one side member and having a mouthpiece affixed thereto, said mouthpiece having an external polygonal flange adapted to fit over the ends of the side members and having an internal arcuate flange adapted to fit into the ends of said members for cooperatively 50 holding them in operative position.

7. A collapsible megaphone comprising flat side members, a handle secured to one side member and having a mouthpiece affixed thereto, said mouthpiece having an external polygonal flange adapted to fit over the ends of the side members and having an internal arcuate flange adapted to fit into the ends of said side members for cooperatively 55 holding them in operative position.

tively holding them in operative position, and means opposite said handle for holding 60 said mouthpiece in position.

8. A collapsible megaphone comprising flat side members, a handle having one end fixed to one of said side members, and being longitudinally slidably and releasably secured thereto adjacent its opposite end, a mouthpiece secured to the last mentioned end of said handle, said mouthpiece being adapted to fit over the ends of said side members. 70

9. A collapsible megaphone comprising flat side members, a handle having one end fixed to one of said side members and being longitudinally slidably and releasably secured thereto adjacent its opposite end, a mouthpiece secured to the last mentioned end of said handle, said mouthpiece being adapted to fit over the ends of said side members, and means on said mouthpiece opposite said handle for holding said mouth- 80 piece in position.

10. A collapsible megaphone comprising flat side members, a handle having one end fixed to one of said side members and being longitudinally slidably and releasably secured thereto adjacent its opposite end, a mouthpiece secured to the last mentioned end of said handle, said mouthpiece having an external polygonal flange adapted to fit over the ends of the side members and having an internal arcuate flange adapted to fit into the ends of said side members for cooperatively holding them in operative position. 90

11. A collapsible megaphone comprising flat side members, a handle having one end fixed to one of said side members and being longitudinally slidably and releasably secured thereto adjacent its opposite end, a mouthpiece secured to the last mentioned end of said handle, said mouthpiece having an external polygonal flange adapted to fit over the ends of the side members and having an internal arcuate flange adapted to fit into the ends of said side members for cooperatively holding them in operative position, and means on said mouthpiece opposite said handle for holding said mouthpiece in position. 100

In witness whereof, I have hereunto set 110 my hand and seal at Racine, Wisconsin, this twenty-third day of March, A. D. nineteen hundred and twenty-three.

ANTHONY C. WEINS. [L. S.]

Witness:

JEROME J. FOLEY.
